Primary Examiner — Susan Bennett Hattan*Assistant Examiner* — Vy Koenig*(74) Attorney, Agent, or Firm* — Foley & Lardner LLP(57) **CLAIM**

We claim the ornamental design for a folded container, as shown and described.

DESCRIPTION

FIG. 1 is a front perspective view of an embodiment of the claimed design;

FIG. 2 is a front view of FIG. 1;

FIG. 3 is a rear view of FIG. 1;

FIG. 4 is a top view of FIG. 1;

FIG. 5 is a bottom view of FIG. 1;

FIG. 6 is a right side view of FIG. 1; and,

FIG. 7 is a left side view of FIG. 1.

The broken lines in the drawings show unclaimed subject matter and form no part of the claimed design. The broken away symbols in the drawings indicate the appearance of any portion of the article between the break lines forms no part of the claimed design.

1 Claim, 5 Drawing Sheets---
